United States Patent Office.

JOHN T. WEBSTER, OF NEW YORK, N. Y., ASSIGNOR TO PAGE, WILDER & CO., OF HALLOWELL, MAINE.

Design No. 3,683, dated September 28, 1869.

DESIGN FOR FLOOR OIL-CLOTH.

The Schedule referred to in these Letters Patent and making part of the same.

To all whom it may concern:

Be it known that I, JOHN T. WEBSTER, of the city of New York, in the county of New York, and State of New York, have originated and designed a new Pattern for Floor Oil-Cloth, of which the following is a full, clear, and exact description, reference being had to the accompanying drawing or printing, making part of this specification.

The drawings, printed in colors, on oiled paper, represent a complete design for floor oil-cloth.

The drawings represent, more fully than any written description, the nature and extent of my invention.

What I claim as my invention, and desire to secure by Letters Patent, is—

The design or pattern for floor oil-cloth or other fabrics, herein set forth.

JOHN T. WEBSTER.
